CLAIM

The ornamental design for a combined bench, golf ball washer and waste receptacle support, as shown and described.

DESCRIPTION

FIG. 1 is a front perspective view of the combined bench, golf ball washer and waste receptacle support of my new design;

FIG. 2 is a front view thereof;

FIG. 3 is a rear view thereof;

FIG. 4 is a side view of the right side thereof;

FIG. 5 is a side view of the left side thereof;

FIG. 6 is a top view thereof;

FIG. 7 is a bottom view thereof;

FIG. 8 is an enlarged sectional view taken along the line 8—8 of FIG. 6 showing the holder for a golf ball washer; and

FIG. 9 is an enlarged sectional view taken along the line 9—9 of FIG. 6 showing the holder for a waste receptacle.

FIG. 1
